(57) **CLAIM**

The ornamental design for a refrigerator, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front-left perspective view of a refrigerator according to the design;

FIG. 2 is a front perspective view thereof;

FIG. 3 is a top-front perspective view thereof;

FIG. 4 is a front elevation view thereof;

FIG. 5 is a back elevation view thereof;

FIG. 6 is a right side elevation view thereof;

FIG. 7 is a left side elevation view thereof;

FIG. 8 is a top plan view thereof;

FIG. 9 is a bottom plan view thereof;

FIG. 10 is a front-left-top perspective view of a section thereof taken along line 10, 11, shown in FIG. 8; and,

FIG. 11 is a front-left-bottom perspective view of a section thereof taken along line 10, 11, shown in FIG. 8.

The evenly broken lines in the drawings depict unclaimed portions of a refrigerator; the dash-dot-dot lines depict unclaimed cross section cut planes; the broken lines form no part of the claimed design.

The portions of the article depicted in dark blue have an appearance that includes a color having the L/a/b colorspace value measured at a 45° angle using a type F/2 illuminant at a 10° angle:

L: 21.99

a: -1.51

b: -12.82

The portions of the article depicted in light grey have an appearance that has a color described as 25% black.
